UNITED STATES PATENT OFFICE.

HOMER L. BOYLE, OF LANSING, MICHIGAN, ASSIGNOR OF ONE-HALF TO SAMUEL H. DAVIS, OF LANSING, MICHIGAN.

VACUUM-CLEANER.

1,299,547.

Specification of Letters Patent.

Patented Apr. 8, 1919.

Application filed January 28, 1915. Serial No. 4,544.

To all whom it may concern:

Be it known that I, HOMER L. BOYLE, a citizen of the United States, residing at the city of Lansing, in the county of Ingham 5 and State of Michigan, have invented a new and useful Vacuum-Cleaner, of which the following is a specification.

My invention relates to improvements in carpet cleaners but more particular the class 10 known as vacuum cleaners, the object of which is to devise a vacuum cleaner whereby the bellows will act in direct connection with the nozzle, in order to minimize the air space.

With the above primary objects and other incidental objects in view, the invention consists of the devices and parts or their equivalents as hereinafter set forth.

In the accompanying drawings, which 20 illustrate my invention, Figure 1, is a side elevation of the device without the brush attachment; Fig. 2, is a similar view with the side of the casing removed to show the internal mechanism; Fig. 3, is a bottom view 25 with the bottom part of the casing removed showing the internal mechanism from the under side; Fig. 4, is a front view, showing the position of the dust sack. Fig. 5, is a front view of the nozzle with the dust sack 30 removed to show the position of the outer valves; Fig. 6, is a back view of the nozzle showing the position of the valves from the inside of the casing; Fig. 7, is a side elevation of the middle board of the nozzle; Fig. 35 8, is an end view of the nozzle; Fig. 9, is a cross-sectional view taken on line 9—9 of Fig. 6; Fig. 10, is a cross-sectional view taken on line 10—10 of Fig. 6; Fig. 11, is a plan view of the frame for attaching the 40 dust sack to the nozzle (Fig. 5); Fig. 12, is an end view of the same showing the spring which holds the nozzle bail securely in place.

Like numerals refer to like parts throughout the several views. In the preferred construction, the cleaner comprises a casing 1 which may suitably be formed of wood or sheet metal and may be of any desired form but preferably as that shown in Fig. 1 and has a handle 2 attached to its sides by means 45 of a bail 3 so that the device may be conveniently pushed over the floor or surface to be

cleaned. Numeral 4 designates a dust sack, made of any woven fabric, the lower end of which is suitably attached to an oblong frame 5 which in turn is held in place over the front of the nozzle 6 by means of a bail 7 which being made of any suitable metal but preferably spring steel has its ends sprung into the metal washers 8, fastened to each side of the casing, and held firmly over the frame 5 by means of steel springs 9; 10 is a hook or other suitable fastening to fasten the other end of the dust sack to the casing to keep the same out of the way from interfering with the moving 60 of the sweeper and to allow plenty of surface for the dust to accumulate in; 11 is a hook or fastening for attaching an ordinary brush carpet sweeper to the rear of the cleaner, for the purpose of gathering the 65 ravelings or loose particles not gathered by the vacuum formed from the working of the bellows.

The nozzle 6 is preferably constructed with pieces of thin wood or other suitable 75 material of 5 to 6 inches in width to about 12 inches long, according to size of sweeper under contemplation. The faces of these pieces are glued or otherwise fastened together, and there are ordinarily three pieces, 80 one forming the front of the nozzle, one the middle thereof and being recessed as described, and the third constituting the back board of the nozzle which is the one that is directly connected with the bellows. In the 85 drawings are shown three openings, which openings are extended through the three pieces, enumerated 12; the completed aperture is then properly covered on the outward 90 surface, as shown in Fig. 5, by properly weighted flap valves (13); which valves are so seated that when opened from the pressure from within, they will again resume their normal positions as coverings over the 95 apertures as the pressure is removed because of the light weight on top of the valve and the suction caused by the receding of the bellows. The middle piece 14^a of the nozzle as illustrated in Fig. 7, is cut or bandsawed out as represented by numeral 14, so that there 100 will be free passages from the mouth of the nozzle to the valves 15 as shown in Fig. 10,

which valves are likewise weighted and seated. The orifice 16 of the nozzle may be protected by a slotted plate to give a smooth surface to come in contact with the floor or article to be cleaned. I do not wish to limit my claims to this specific construction of the nozzle as the same principle may be consummated by making the nozzle of two pieces or even one piece instead of three, and the 10 valves may be placed side by side or one above another. As shown in Fig. 3 there are three bellows (17) attached directly to the nozzle, respectively covering the three sets of valves. While I have shown three bellows and three sets of valves, a sweeper may be constructed that will not depart from my invention having any number of bellows and corresponding valves. 18 and 19 designate the front and backboards of the bellows, being preferably constructed of square blocks of wood, a collapsible material surrounding the two, forming an air tight compartment, but for the valve openings in the bellows boards (18). Numeral 20 designates 15 stays pivoted to the top of the casing and the lower corner of the bellows board 19, so that it may move back and forth with the motion of the bellows to keep the same in position. Secured centrally to the bellows 20 boards 19 by brackets 21 are pitmen (22), of fiber or other suitable material, the other ends of which are attached off center to the drive wheels (23) or to the axle (24) which connects the drive wheels, the axle having 25 a crook (25) which forms a crank or turn for the purpose, so that when the sweeper is moved along the surface to be cleaned it will be seen that the bellows boards will be reciprocated to actuate the bellows. As the 30 bellows are in direct connection with the valves to the nozzle, they will have a tendency to draw in the dust laden air from the floor or surface to be cleaned through the orifice (16), which, being directly connected 35 with the inner valve 15, will allow the dust laden air to enter the bellows, and as each bellows is being closed by the pressure of the pitman against the bellows board 19 the pendant flap valve 15 will close and the air 40 and dust will be exhaled or forced through the outer valves 13 into the dust receptacle 4, which is made of a foraminous material that acts as a strainer, allowing the air to escape but retaining all dust and dirt. 45 It will thus be particularly noted that I have constructed a bellows sweeper, whereby by connecting the bellows directly with the nozzle, I have minimized the air space to the small aperture in the nozzle itself designated by 14 as shown in Fig. 7. The dust 50 sack may be cleaned at any time by raising the bail 7, which allows the frame 5 to be removed and the sack thoroughly cleaned without disturbing or raising the cleaner 55 from the floor.

In the operation of this invention, as will be noted in Figs. 9 and 10 particularly, the fixed bellows board is also the nozzle, having a hollow interior open at the bottom by way of which the dirt is sucked up, and the hollow interior opens almost directly into the bellows. By this construction a very quick, strong suction is attained, and the cleaning effect correspondingly augmented.

I claim:

1. In a vacuum cleaner, the combination with bellows-working means, of a bellows having a fixed chambered bellows board, the said board having a hollow interior opening downwardly whereby the board forms the nozzle of the cleaner, the said board having orifices opening into the bellows, inlet valves controlling the said orifices, the said bellows board having openings passing through it, and outlet valves exteriorly controlling the said openings through the bellows board.

2. In a vacuum cleaner, the combination with a nozzle, of a bellows having its folding portion directly connected with the nozzle whereby the nozzle constitutes the relatively fixed board of the bellows, means for operating the bellows, the nozzle having orifices opening into the bellows, inlet valves controlling the said orifices, the said nozzle having openings passing through it, outlet valves exteriorly controlling the said openings, and a dust receiver connected with the nozzle exteriorly, the mouth of the dust receiver being arranged over the said outlet valves.

3. In a vacuum cleaner, the combination with a nozzle, of a bellows having its folding portion directly connected with the nozzle whereby the nozzle constitutes the relatively fixed board of the bellows, means for operating the bellows, the said nozzle having orifices opening into the bellows, inlet valves controlling the said orifices, the said nozzle having a portion projecting exteriorly and openings passing directly through the nozzle and through the said projecting portion thereof, outlet valves arranged exteriorly upon the said projecting portion of the nozzle and controlling the said openings, a dust receiver arranged with its mouth covering the said projecting portion and outlet valves, and removable means for securing the mouth of the dust receiver in place.

4. In a vacuum cleaner, the combination with a casing of a nozzle having a vertical side, a bellows having its folding portion connected directly with said vertical side of the nozzle whereby the nozzle constitutes the relatively fixed board of the bellows, the said bellows having a movable board attached to the said folding portion, stays pivotally attached to the top of the said casing and to the said movable board for supporting the said board, means for moving

the movable board toward and from the said nozzle to operate the bellows, the said nozzle having orifices opening into the bellows, inlet valves controlling the said orifices, the 5 said nozzle having openings passing through it, outlet valves exteriorly controlling the said openings, and a device connected with the said nozzle exteriorly and arranged to receive dust from the said outlet valves.

HOMER L. BOYLE.
